United States Patent Office

Des. 205,132
Patented June 28, 1966

205,132

AUTOMOBILE

Ferdinand Alexander Porsche, Jr., Boblingen Germany,
assignor to Firma Dr. Ing. h.c. F. Porsche K.G., Stuttgart-Zuffenhausen, Germany

Filed Sept. 9, 1965, Ser. No. 86,913

Term of patent 14 years

(Cl. D14—3)

FIG.1

FIG.2

FIG.3

FIG.4

FIG5

FIG.6

FIG.7

FIG.8

FIGURE 1 is a perspective view of the automobile embodying my new design, viewing the automobile from the left side thereof;

FIGURE 2 is a right side elevational view thereof;

FIGURE 3 is a front elevational view thereof;

FIGURE 4 is a rear elevational view thereof;

FIGURE 5 is a top plan view thereof;

FIGURE 6 is a right elevational view thereof, with the front portion of the convertible top removed;

FIGURE 7 is a view similar to FIGURE 6, with the rear portion of the convertible top removed; and

FIGURE 8 is a view similar to FIGURES 6 and 7, with both the front and rear portions of the convertible top removed.

The essential features of the design reside in the portions shown in full lines.

I claim:

The ornamental design for an automobile, as shown and described.
